BUFFING DEVICE

Frank P. Bitomley, East Orange, N. J.; Katherine Bitomley, executrix of said Frank P. Bitomley, deceased

Application January 26, 1950, Serial No. 140,629

10 Claims. (Cl. 51—193)

1

This invention relates to buffing devices and articles therefor, and more especially to such devices having multi-layered annular textile material normally employed in buffing devices and certain hereinafter-disclosed novel means for securing said textile material.

Important objects of the present invention are to provide buffing wheels and the like which are truly circular in external periphery so as to avoid the "bumping" action resulting from the use of buffing wheels which are not truly circular. Another object is the provision of buffing wheels which have greater charring resistance than those about which I am aware. Further objects are to provide buffing wheels easy to make and assemble. A still further object of this invention is the provision of a rigid novel disc-like securing means for the textile material.

With the foregoing in mind my present invention consists of certain novel features of construction and method of assembly, all of which will be more fully hereinafter described and which will become apparent from the following detailed description taken in connection with the accompanying drawings in which like characters represent like parts throughout and which form a part hereof.

In the drawings:

Fig. 1 is a top plan view of a novel disc-like member suitable for use in accordance with my invention in connection with textile materials to form a buffing wheel;

Fig. 2 is a fragmentary top plan view of my novel buffing wheel;

Fig. 3 is a cross section taken along the line 3—3 of Fig. 2; and

Fig. 4 is a cross section taken along the line of 4—4 of Fig. 1.

Referring to the drawings, which show a preferred embodiment of my invention, the buffing wheel 10 comprises an outer annular textile portion 11 and a centrally-located, rigid, disc-like portion 12 which secures the textile portion 11 near and along the length of the inner periphery 13 thereof.

My invention is not restricted to any particular type of buffing fabric, any suitable textile material such as muslin, shirting, denim, or high grade bias cut cotton being suitable. The fabric, advantageously high grade bias cut cotton, is arranged in known manner in annular form to form radially disposed reverse folds 14.

The textile securing means 12 comprises two identical disc-like members 15, each of which has a small central opening 16 and flange 17

2

so as to permit the buffing wheel to be placed on a suitable shaft or spindle (not shown). The discs 15 comprise three main portions; an inner flat portion 18, a wall portion 19, suitably making an angle of 90° with and extending from the periphery 20 of said inner portion; and an outer annular portion 23, suitably substantially parallel to the inner portion 18. It will be understood that the discs 15 are one-piece or integral units and may be made of any suitable rigid material, e. g., a metal stamping.

The inner portion 18 of each disc 15 has at least one eccentrically-located opening 21. Where a plurality of such openings 21 is provided they are symmetrically and uniformly disposed around the central opening 16. I have found it especially advantageous so to locate the eccentrically-located holes 21 as to cause them to extend beyond the wall 19 of the disc 15, thereby providing an air passage between the holes 21 and the channel 22, hereinafter more particularly described. The openings 21 may be of any desired form; such as oval (as shown), circular, etc.

25 The outer portion 23 of the novel disc 15 of my invention has, advantageously, a series of holes 24 extending near and around the inner periphery 25 of said outer portion 23. Also provided as part of the outer portion 23 of my novel disc are ribs 26 of suitable size, these ribs 26 furnishing air space for cooling purposes when more than one buffing wheel made in accordance with my present invention is employed serially, in accordance with common practice.

30 Located around the outer periphery 20 of the outer portion 23 of my disc 15 are a number of teeth 27. The teeth 27 are so located that the tip 28 of any tooth 27 located nearest the line, e. g., 29, drawn from the center of the central opening 16 in the disc 15 through the center of any of the eccentrically-located openings 21 is a distance from said line equal to one fourth the distance between any two adjacent tooth tips. Further, it is important that the correct number of teeth be employed. I have found that any number of teeth may be employed provided they entirely encircle the outer periphery 20 of the outer portion of the disc and provided further that the number of eccentrically-located openings 21 is exactly divisible into the number of teeth 27.

35 In assembling my novel buffing wheel 10, two identical discs 15 are placed back-to-back (see Fig. 3) so that the central openings 16 and eccentrically disposed openings 21 of each coincide,

40 45 50 55

The two discs are then joined together into a single unit, by any suitable means, for example, by spot welding, as indicated at 31 in Fig. 2 or by riveting, etc.

The folded fabric 11 is brought into contact by known means with the joined discs; the outer portion of the joined discs is opened up so as to receive the inner edge of the folded fabric 11, and the teeth 27 are caused to be clamped into the fabric so that each tooth tip 28 engages the low point 32 of a fold 14. Because of the unique structure of the joined discs the teeth of one of the joined discs will be in staggered relation with the corresponding teeth of the other joined disc, the distance between the teeth in clamped relation being one half the distance between adjacent teeth on each of the joined discs. Also, the holes 24 of one of the joined discs will be in staggered relation with corresponding holes 24 of the other disc.

I have found it advantageous so to attach the joined discs to the textile material as to permit an annular channel 22 to exist between the holes 24 of the joined discs and the inner peripheral edge 13 of the textile material. This perhaps can be best noted from Fig. 3.

By reason of the fact that the eccentrically-located holes 21 extend beyond the walls 19 of the disc 15 a passage for air flow is formed through the eccentrically-located holes 21 into the channel 22 and out of the small holes 24 in the outer portion of the disc, thereby obtaining a cooling effect which is desirable in buffing devices.

While I have described my invention in detail in its preferred embodiment, it will be obvious to those skilled in the art, after understanding my invention, that various changes and modifications may be made therein without departing from the spirit or scope thereof. I aim in the appended claims to cover all such modifications and changes.

I claim:

1. A rigid, integral, disc-like device suitable for use in connection with textile material to form a buffing wheel, comprising an inner portion of circular periphery having a centrally-located opening and at least one eccentrically-located opening, said latter openings being symmetrically and uniformly disposed around the central opening when present in a number greater than one, a wall portion making an angle of substantially 90° with and extending from the periphery of said inner portion, and an outer portion substantially parallel to said inner portion, teeth located around the outer periphery of said outer portion, said teeth being numerically integrally divisible by the number of said at least one eccentrically-located opening and being so located that the tip of the tooth located nearest the line drawn from the center of said central opening in the disc-like device through the center of any of said at least one eccentrically-located opening is a distance from said line equal to one fourth of the distance between adjacent tooth tips.

2. A rigid, integral, disc-like device suitable for use in connection with textile material to form a buffing wheel, comprising an inner portion of circular periphery having a centrally-located opening and at least one eccentrically-located opening, said latter openings being symmetrically and uniformly disposed around the central opening when present in a number greater than one, a wall portion making an angle of substantially 90° with and extending from the periphery of said inner portion, and an outer portion substantially

parallel to said inner portion, teeth located around the outer periphery of said outer portion, said teeth being numerically integrally divisible by the number of said at least one eccentrically-located opening and being so located that the tip of the tooth located nearest the line drawn from the center of said central opening in the disc-like device through the center of any of said at least one eccentrically-located opening is a distance from said line equal to one fourth of the distance between adjacent tooth tips, and holes located near and around the inner periphery of said outer portion.

3. A rigid, integral, disc-like device suitable for use in connection with textile material to form a buffing wheel, comprising an inner portion of circular periphery having a centrally-located opening and at least one eccentrically-located opening, said latter openings being symmetrically and uniformly disposed around the central opening when present in a number greater than one, a wall portion making an angle of substantially 90° with and extending from the periphery of said inner portion, and an outer portion substantially parallel to said inner portion, teeth located around the outer periphery of said outer portion, said teeth being numerically integrally divisible by the number of said at least one eccentrically-located opening and being so located that the tip of the tooth located nearest the line drawn from the center of said central opening in the disc-like device through the center of any of said at least one eccentrically-located opening is a distance from said line equal to one fourth of the distance between adjacent tooth tips, and holes located near and around the inner periphery of said outer portion.

4. A rigid, integral, disc-like device suitable for use in connection with textile material to form a buffing wheel, comprising an inner portion of circular periphery having a centrally-located opening and a plurality of eccentrically-located openings symmetrically and uniformly disposed around said central opening, a wall portion making an angle of substantially 90° with and extending from the periphery of said inner portion, and an outer portion substantially parallel to said inner portion, teeth located around the outer periphery of said outer portion, said teeth being numerically integrally divisible by the number of eccentrically-located openings and being so located that the tip of the tooth located nearest the line drawn from the center of said central opening in the disc-like device through the center of any of said eccentrically-located openings is a distance from said line equal to one fourth of the distance between adjacent tooth tips, and holes located near and around the inner periphery of said outer portion, said device being further characterized by the fact that said eccentrically-located holes extend through said wall and beyond the inner periphery of said outer portion.

5. A buffing device comprising multi-layered, annular textile material suitable for buffing devices and means for securing the inner periphery of said textile material, said means comprising two rigid, integral, disc-like devices each of which comprises an inner portion of circular periphery having a centrally-located opening and at least one eccentrically-located opening, said latter openings being symmetrically and uniformly dis-

posed around the central opening when present in a number greater than one, a wall portion making an angle of substantially 90° with and extending from the periphery of said inner portion, an outer portion substantially parallel to said inner portion, and teeth located around the outer periphery of said outer portion, said teeth being numerically integrally divisible by the number of said at least one eccentrically-located opening and being so located that the tip of the tooth located nearest the line drawn from the center of said central opening in the disc-like device through the center of any of said at least one eccentrically-located opening is a distance from said line equal to one-fourth of the distance between adjacent tooth tips, said two rigid devices being rigidly secured together in back-to-back engagement so that the said at least one eccentrically-located opening of one disc coincides with the said at least one eccentrically-located opening of the other disc and said teeth are in clamping engagement with the textile material near and around the inner periphery thereof, the teeth of one disc being in staggered relation to the teeth of the other disc.

6. A buffing device comprising multi-layered, annular textile material suitable for buffing devices and means for securing the inner periphery of said textile material, said means comprising two rigid, integral, disc-like devices each of which comprises an inner portion of circular periphery having a centrally-located opening and at least one eccentrically-located opening, said latter openings being symmetrically and uniformly disposed around the central opening when present in a number greater than one, a wall portion making an angle of substantially 90° with and extending from the periphery of said inner portion, an outer portion substantially parallel to said inner portion, teeth located around the outer periphery of said outer portion, said teeth being numerically integrally divisible by the number of said at least one eccentrically-located opening and being so located that the tip of the tooth located nearest the line drawn from the center of said central opening in the disc-like device through the center of any of said at least one eccentrically-located opening is a distance from said line equal to one-fourth of the distance between adjacent tooth tips, and holes located near and around the inner periphery of said outer portion, said two rigid devices being rigidly secured together in back-to-back engagement so that the said at least one eccentrically-located opening of one disc coincides with the said at least one eccentrically-located opening of the other disc and said teeth are in clamping engagement with the textile material near and around the inner periphery thereof, the teeth of one disc being in staggered relation to the teeth of the other disc.

7. A buffing device comprising multi-layered, annular textile material suitable for buffing devices and means for securing the inner periphery of said textile material, said means comprising two rigid, integral, disc-like devices each of which comprises an inner portion of circular periphery having a centrally-located opening and at least one eccentrically-located opening, said latter openings being symmetrically and uniformly disposed around the central opening when present in a number greater than one, a wall portion making an angle of substantially 90° with and extending from the periphery of said inner portion, an outer portion substantially parallel to said inner portion, teeth located around the outer periphery of said outer portion, said teeth being numerically

integrally divisible by the number of said at least one eccentrically-located opening and being so located that the tip of the tooth located nearest the line drawn from the center of said central opening in the disc-like device through the center of any of said at least one eccentrically-located opening is a distance from said line equal to one-fourth of the distance between adjacent tooth tips, and holes located near and around the inner periphery of said outer portion, said devices being further characterized by the fact that said eccentrically-located holes extend through said wall and beyond the inner periphery of said outer portion, said two rigid devices being rigidly secured together in back-to-back engagement so that the said at least one eccentrically-located opening of one disc coincides with the said at least one eccentrically-located opening of the other disc and said teeth are in clamping engagement with the textile material near and around the inner periphery thereof, the teeth of one disc being in staggered relation to the teeth of the other disc.

8. A buffing device comprising multi-layered, annular textile material suitable for buffing devices and means for securing the inner periphery of said textile material, said means comprising two rigid, integral, disc-like devices each of which comprises an inner portion of circular periphery having a centrally-located opening and a plurality of eccentrically-located openings symmetrically and uniformly disposed around the central opening, a wall portion making an angle of substantially 90° with and extending from the periphery of said inner portion, an outer portion substantially parallel to said inner portion, teeth located around the outer periphery of said outer portion, said teeth being numerically integrally divisible by the number of eccentrically-located openings and being so located that the tip of the tooth located nearest the line drawn from the center of said central opening in the disc-like device through the center of any of said eccentrically-located openings is a distance from said line equal to one fourth of the distance between adjacent tooth tips, and holes located near and around the inner periphery of said outer portion, said devices being further characterized by the fact that said eccentrically-located holes extend through said wall and beyond the inner periphery of said outer portion, said two rigid devices being rigidly secured together in back-to-back engagement so that the eccentrically-located openings of one disc coincide with the eccentrically-located openings of the other disc and said teeth are in clamping engagement with the textile material near and around the inner periphery thereof, the teeth of one disc being in staggered relation to the teeth of the other disc.

9. A rigid, integral, disc-like device suitable for use in connection with textile material to form a buffing wheel, comprising an inner portion of circular periphery having a centrally located opening and a plurality of eccentrically-located openings symmetrically and uniformly disposed around the central opening, a wall portion making an angle of substantially 90° with and extending from the periphery of said inner portion, an outer portion substantially parallel to said inner portion, teeth located around the outer periphery of said outer portion, said teeth being numerically integrally divisible by the number of eccentrically-located openings and being so located that the tip of the tooth located nearest the line drawn from the center of said central

opening in the disc-like device through the center of any of said eccentrically-located openings is a distance from said line equal to one fourth of the distance between adjacent tooth tips, and holes located near and around the inner periphery of said outer portion, said device being further characterized by the fact that said eccentrically-located holes extend through said wall and beyond the inner periphery of said outer portion, and ribs on said outer portion.

10. A buffering device comprising multi-layered, annular textile material suitable for buffering devices and means for securing the inner periphery of said textile material, said means comprising two rigid, integral, disc-like devices each of which comprises an inner portion of circular periphery having a centrally-located opening and a plurality of eccentrically-located openings symmetrically and uniformly disposed around the central opening, a wall portion making an angle of substantially 90° with and extending from the periphery of said inner portion, outer portion substantially parallel to said inner portion, teeth located around the outer periphery of said outer portion, said teeth being numerically integrally divisible by the number of eccentrically-located openings and being so located that the tip of the tooth located nearest the line drawn from the center of said central opening in the disc-like device through the center of any of said eccentrically-located openings is a distance from said

5 line equal to one fourth of the distance between adjacent tooth tips, and holes located near and around the inner periphery of said outer portion, ribs on said outer portion, said devices being further characterized by the fact that said eccentrically-located holes extend through said wall and beyond the inner periphery of said outer portion, said two rigid devices being rigidly secured together in back-to-back engagement so that the 10 eccentrically-located openings of one disc coincide with the eccentrically-located openings of the other disc and said teeth are in clamping engagement with the textile material near and around the inner periphery thereof, the teeth of one disc 15 being in staggered relation to the teeth of the other disc.

FRANK P. BITOMLEY.
